UNITED STATES PATENT OFFICE

JOHN R. REPROGLE, OF DETROIT, MICHIGAN, ASSIGNOR TO KELVINATOR CORPORATION, OF DETROIT, MICHIGAN, A CORPORATION OF MICHIGAN

REFRIGERATING APPARATUS

Original application filed February 28, 1921, Serial No. 448,331, and in Canada February 11, 1922. Divided and this application filed June 10, 1927. Serial No. 197,942.

This invention relates to mechanical refrigeration apparatus and to such as are particularly adapted for domestic use, the present application being a division of my co-pending application Serial No. 448,331, filed February 28, 1921.

An object of this invention is to provide an improved refrigerating system having as an essential element thereof a cooling unit of improved construction and arrangement of parts.

Another object is to provide an improved arrangement of the cooling unit parts with respect to the air circulating openings in the cooling chamber of a refrigerator cabinet.

Another object is to provide a vaporizer for said cooling unit of improved construction and arrangement of parts.

Another object is to provide an improved arrangement of vaporizer parts with respect to a brine tank and also with respect to a chamber located in said brine tank, which chamber is adapted to receive material to be chilled or frozen such as food, water and the like.

Other objects more or less incidental or ancillary to the foregoing will be apparent to those skilled in the art from an examination of the following description in connection with the accompanying drawing.

In the drawings:

Fig. 1 is a front elevation of a refrigerator assembly with some parts shown in section and other parts broken away.

Fig. 2 is a vertical sectional view of the cooling chamber of this refrigerator, the said section being taken at right angles to Fig. 1.

Fig. 3 is an enlarged side elevation of the refrigerating or brine tank, with the vaporizer therein, some parts being broken away and some being shown in section.

Fig. 4 is a front elevation of the device shown in Fig. 3, some parts being broken away and some being shown in section.

I have shown in Figs. 1 and 2 a mechanical refrigerator cabinet 1 which is divided, as shown, by a horizontal partition wall 2 into a refrigerator compartment 3 and a machine compartment 4. The exterior top, bottom, front, back and end walls of this cabinet are

designated by the reference characters 5, 6, 7, 8 and 9 respectively. These walls are rigidly secured together in any convenient manner and are braced by means of suitable bars 10 as shown in Fig. 2. A lining of insulating material 11 is provided for the refrigerator compartment 3. It will be noted that the lining provided at the ends and back of this compartment is spaced from the exterior walls of the cabinet; which construction, as will be readily understood, provides a dead air heat insulating space 12 between the refrigerator compartment 3 and the exterior walls thereof.

Located within or adjacent to the compartment 3 as for example at one side and within the upper portion thereof, is a relatively small refrigerating or cooling chamber 14 open at its front end and closed by the door 15. (See Figs. 1 and 2.) The walls of the compartment 3 may form two sides and the top of this chamber. The remaining side 16 and the bottom 17 of this chamber also may be provided with heat insulating material, although this is not necessary. A lining 18 of any suitable material forms the interior walls of this chamber. Two openings are provided one above the other for the thermo-siphonic circulation of air through the chamber. As shown, the side wall 16 is provided at its upper end with an inlet opening 19 and the bottom wall 17 is provided with an outlet opening 20 for such circulation of air.

A thermostatically controlled damper mechanism 21 which constitutes the subject of my Patent No. 1,652,216 patented Dec. 13, 1927, controls the circulation of air through the opening 20 in a manner which will be readily understood.

The arrangement of the cooling chamber provides a continuous L-shaped food compartment 22, one part thereof extending vertically along the side of the cooling chamber 14 and the other laterally beneath the said chamber. This food compartment is lined with porcelain or enameled material, as is common in such structures. This compartment 22 is closed by any convenient arrangement of doors. As shown, this is accomplished by means of the full length main

door 23, and a smaller door (not shown) located beneath the door 15.

Within the cooling chamber and between the inlet and outlet openings 19 and 20, I have positioned a refrigerating or cooling unit 24 which forms an essential part of my mechanically operated refrigerating system. This cooling unit occupies a central position within the cooling chamber and is spaced 10 from the top, bottom, and side walls thereof so as to permit a free circulation of air through the said chamber and about the cooling unit. The food compartment 22 is so arranged with respect to the cooling chamber 15 and the air circulating openings 19 and 20 as to permit a thermo-siphonic circulation of air through the food compartment and cooling chamber. The warm air rising from the food contained in the compartment 22 will 20 flow through the inlet opening 19 and into the cooling chamber 14, wherein its temperature is lowered as it comes into contact with the cooling unit and as a result flows downward and about the unit and passes through 25 the outlet opening 20 and into the lower part of the compartment 22 wherein its temperature is again raised as it performs its functions of cooling the food contained therein. The thermostatically controlled damper 30 mechanism 21 referred to above regulates the circulation of this air through the food compartment and cooling chamber.

The machine compartment 4 in the lower portion of the cabinet 1 is adapted to contain a motor-compressor-condenser unit. It is to be noted that in the broader aspects of my invention it is not essential that this machine compartment be included in the cabinet as the compressor can be installed in a remote 40 position such as the basement or a different room of the building. This machine compartment is adapted to be tightly closed by means of a suitable door (not shown) so that any noise of the operating mechanism within 45 will be reduced to a minimum.

Within the machine compartment 4 I have installed, as was stated, the motor-compressor-condenser unit which forms an essential part of a refrigerating system which maintains a low temperature in the refrigerator compartment 3. This unit comprises an electric motor 25, a compressor 26 driven by the motor, and a water cooled condenser 27. The compressor is adapted to receive vaporized refrigerant through its suction inlet, compress the vapor and discharge it into the condenser where the combined pressure and cooling liquefy it. The motor-compressor-condenser unit will not be described in detail since, so 50 far as the present invention is concerned, the compressor-condenser unit may have any suitable detail construction, and indeed, so far as some aspects of the invention are concerned, any apparatus can be used that is adapted to liquefy refrigerant vapor. How-

ever, it is observed that the unit shown in the drawings is described in detail in my application Serial No. 448,331, above referred to.

The suction side of compressor 26 is connected by a conduit 28 with the vapor space 70 of a vaporizer 29 forming an essential part of the cooling unit 24 referred to above. The discharge port of the condenser is connected by a conduit 30 to the refrigerant inlet of the said vaporizer 29, said conduit being 75 adapted to conduct liquid refrigerant to the vaporizer from the condenser. Any suitable refrigerant can be employed in so far as some features of the invention are concerned, but I prefer to use sulphur dioxide (SO_2).

I prefer to use as a lubricant for the working parts of my refrigerant system a suitable mineral oil. Such an oil and liquid sulphur dioxide are highly but not completely mutually soluble, and also the oil is of lower specific gravity than the said refrigerant. This oil is initially charged into the crank case 80 of the compressor to a level slightly below the lowest point of travel of the working piston thereof, so that during the operation the said oil will be splashed on the various journals and into the working cylinders and thereby thoroughly lubricate the moving parts and form a liquid seal for the working piston. Some of the oil will be forced into the condenser along with the compressed vapor, wherein it will become absorbed by or dissolved in the liquefied SO_2 and from there be forced through the conduit 30 along with the liquid SO_2 into the vaporizer 29.

The cooling unit 24 is supported within the cooling chamber by means of the U-shaped straps 31, and comprises in addition to the vaporizer 29 referred to above, a brine tank 32. The said brine tank carries in the upper left hand portion thereof an expansion chamber or header 33 which forms a reservoir for a substantial volume of the liquid SO_2 and oil (see Figs. 4 and 5). A plurality of refrigerant circulating pipes bent to form loops 34 depend from the said header and are disposed within the brine tank. Each of the pipe loops is connected at one end 35 to the side wall 36 of the header at a point near the bottom thereof and is connected at its other end 37 to the said side wall at a point spaced from and at a higher level than said first named connection. The pipe loops 34 are arranged in planes parallel to each other and at right angles to the side wall 36 of the header 33, and define a continuous space 38 below the said header. It is to be noted also that the pipe loops are arranged unsymmetrically with relation to a vertical plane passing through the longitudinal axis of the header so as to facilitate a compact arrangement of the parts of the vaporizer and the brine tank, and at the same time permit the symmetrical disposition of the pipes within said tank. The mid portions of the 100

pipe loops are secured together by means of the bracing strip 39, so as to prevent any injury due to their relative movement or their movement with respect to the header 33 which might result from rough handling.

5 The header 33 is closed at its front end by means of a removable end plate 40 and is adapted to contain liquid refrigerant and oil. The oil which is pumped into the header in 10 solution in the SO₂ liquid is left behind in the distillation of that liquid and being of lower specific gravity than the latter floats on the same. The removable end plate 40 is provided with an inlet passage 41 through the 15 lower portion thereof and also with an outlet passage 42 therethrough at a point spaced from and at a substantial distance above the said inlet opening. The conduit 30 which conducts the liquid SO₂ and oil in solution 20 from the condenser 27 is secured to the end plate 40 within the said inlet opening 41 and the return conduit 28 is secured to the said end plate within the outlet opening 42. The removable end plate 40 is secured to the 25 header by means of the bolts 43, 43. By unscrewing the bolts 43, 43 the plate can be entirely removed from the cooling unit without disturbing the wall surface of the brine tank.

The end plate 40 carries on its inner side a 30 needle valve 44 which controls the flow of liquid SO₂ and oil through the inlet passage 41. The needle valve 44 is operated by means of a float stem 45 which is pivotally secured at 46 to an extension of the end plate. A float 35 47 is rigidly secured to the free end of the stem 45 and is so arranged or calibrated that it floats in the two liquids as shown in such a manner that should the liquid refrigerant rise above a predetermined height, the 40 needle valve will be closed by the action of the float, a comparatively fixed level of the liquid refrigerant being thus maintained. The float stem 45 has shoulders 48 that are 45 adapted to engage the finger 49 on the end plate 40 to limit the upward and downward movements of the float. A slotted projection 50 on the float stem 45 engages a pin 51 on one end of an inverted U-shaped spring 52 the other end of which is secured to the rear 50 of the expansion or needle valve 44. A stirrup or keeper 53 secured with the spring to the valve and extending about the float end of the spring permits a spring action in seating the valve but affords a positive action 55 in withdrawing it. By interposing the spring between the projection on the float valve stem and the needle valve, all danger of jamming the needle valve into seat in the restricted passage 41 with the attendant injury to, and 60 sticking of, the valve is eliminated.

The outlet passage 42 is located at an appreciable distance above the level of the liquid SO₂ in the header so as to reduce as much as possible the likelihood of any liquid SO₂ escaping therethrough. A tube 54 is at-

tached to the inner end of this passage and has its free end extending inwardly and upwardly above the oil level and communicating at its upper end with the vapor space of the header. Openings 55 in the mid portions of this tube 70 permit the oil floating on the surface of the SO₂ to flow into the pipe 28 when the level of that oil rises above a predetermined height. Due to the violent boiling at times of the liquid SO₂, particularly when liquid is admitted by the float valve, it has been found that the spacing of the outlet passage above the level of the liquid SO₂ is not sufficient to prevent the escape of the liquid SO₂ there-through. To further insure against the escape of this liquid I have positioned a baffle plate 56 directly beneath the opening so as to direct the flow of any boiling liquid away from the passage 42. The baffle plate 56 is 75 also conveniently carried by the removable end plate 40 of the header as shown.

The liquid refrigerant is forced under pressure through the passage 41 into the header where a low pressure is maintained by the suction of the compressor, thus permitting the liquid SO₂ to boil or vaporize and in so doing to lower the temperature of the brine as well as the liquid SO₂ itself. The float valve mechanism maintains the 90 level of the liquid SO₂ above the uppermost ends 37 of the pipe loops 34, and as heat is absorbed through the walls of the pipe loops a circulation is set up through the pipe loops of the liquid refrigerant in the header and in said loops. This circulation increases the 95 efficiency of the vaporizer.

The oil that overflows into the outlet passage 42 will contain some liquid SO₂ in solution and in order to make use of this, the return pipe 28 through which the SO₂ vapor and oil are drawn by the compressor is arranged in loops or sinuations with the sections 57 slightly inclined and arranged between the walls of the cooling chamber and the brine tank as shown in Figs. 1 and 2. The oil as it moves slowly along under the influence of gravity has the SO₂ evaporated out of it by the decrease in pressure and the absorption of heat from the air in the cooling chamber. Due to the position of the conduit 28 within the cooling chamber some of the warm air entering the chamber will first contact with the conduit 28 and as a result hasten the evaporation of the liquid SO₂ contained therein. Thus the SO₂ held in solution in the oil is effectively utilized as a refrigerant during its return to the compressor.

In the interest of compactness the upper ends of the conduits 28 and 30 are arranged above the brine tank and between the header and the warm air inlet opening and attached to the end plate 40 in the manner above described. The intermediate portions of these conduits may, if desired, be embedded in the insulating material of the back wall in jux-

5 taposition to each other whereby the liquid refrigerant within the pipe 30 will be somewhat further cooled by giving up a portion of its heat to vaporize the refrigerant particles remaining in solution in the oil in the pipe 28.

10 The brine tank 32 is constructed of any suitable heat conducting material and has one or more series of aligned openings formed in the front and rear walls thereof. Three such 15 series are shown. These openings are adapted to be closed by means of elongated tubular sleeves which form part of the wall structure of the tank, the joints between the sleeves and the said tank walls being, of course, liquid tight. The sleeves 58 are arranged within the space 38 defined by the pipe loops and constitute food chambers adapted to receive trays or any suitable receptacles 59 for the 20 chilling of edibles or the freezing of ice, as the case might be. At 60 I have shown an opening adapted to be sealed by means of a plug 61 and through which the tank may be filled with any suitable heat conducting medium 25 having a comparatively low freezing point, preferably calcium chloride ($CaCl_2$) solution.

30 It will be seen that the cooling unit consists essentially of a vaporizer, comprising header and depending pipe loops, and a brine tank in the brine of which the vaporizer is partly immersed. A cover or finishing plate 32 closes the front of the cooling chamber and prevents the warm outside air from entering 35 during the period that the outer door 15 is open. The openings 63 are provided in this plate for the insertion of the food trays into the cooling unit.

40 As stated, the expansion chamber or header 33 is supported within the upper left hand portion of the brine tank. As can be seen from an examination of Figs. 1 and 4, the upper portion of the header projects above the top wall of the brine tank and is exposed 45 to the warm air first entering the cooling chamber. Due to the expansion and contraction of the brine solution in the tank 32 it is impossible to keep the tank completely full. This results in the top wall of the brine tank 50 being appreciably warmer than the remaining walls thereof. As the liquid refrigerant contained within the header is even colder than the brine solution the walls of the header would be of a correspondingly low temperature. Therefore, the upper portion of 55 the header is effectively used to absorb heat from the warm air first entering the cooling chamber 14 and conduct it directly to the liquid refrigerant in the vaporizer 29.

60 It is to be noted that the top of the brine tank is substantially flush with the lower part of the warm air inlet opening 19 and that the header is positioned unsymmetrically with relation to the brine tank at a point remote from this warm air opening. Due to

70 this arrangement the warm air can freely enter the chamber and some of it will completely fill the upper portions thereof before it starts the downward circulation around the brine tank. Due to the thorough circulation of the air about the brine tank the remote left hand wall thereof is effectively utilized as a cooling surface.

75 In positioning the brine tank centrally of the cooling chamber with its top surface arranged below the warm air inlet opening; and in mounting the header within the brine tank with the upper portion thereof projecting above the top surface of the brine tank and positioned at a point remote from the 80 said warm air inlet opening; and in arranging the return refrigerant conduit between the brine tank and the wall of the cooling chamber at a point adjacent the said warm air inlet opening; I have provided a highly 85 compact and efficient arrangement of cooling unit parts which will effectively cool the air circulating through the said cooling chamber.

90 The unsymmetrical arrangement of the depending pipe loops 34 with respect to a vertical plane passing through the longitudinal axis of the header 33 permits the header to be positioned at a point remote from the warm air inlet opening 19 and at the same time permits an even disposition of the pipe loops within the brine tank, which results in an even temperature of the brine solution and an even freezing of the articles contained 95 in the centrally located sleeves 58. In addition the unsymmetrical arrangement of the pipe loops gives ample space for the tube ends and their connections with the side wall of the header, and also with a maximum of compactness, it permits the ends 35 to be 100 connected to the bottom of the header wall which latter is desirable to promote the circulation of liquid SO_2 through the loops.

105 By arranging the expansion chamber and brine tank so that the removable end plate is accessible from the front of the cooling unit, and by supporting the float controlled needle valve and the baffle plate from this removable end plate, and by providing the plate with both the refrigerant inlet and outlet 110 passages, I have provided a compact, convenient, and simple arrangement of parts, 115 which is highly desirable from the standpoint of assembly and repair.

120 While I have shown and described in some detail the preferred construction and arrangement of parts it will be understood that in all respects there can be wide variation without departing from the invention as defined in the appended claims.

125 What I claim as my invention is:

1. In a mechanical refrigerating apparatus, the combination of means for liquefying a gaseous refrigerant; a vaporizer of the flooded type comprising a header and plu- 130

rality of pipe loops depending from the header each with its ends opening into said header at different levels; a conduit to conduct liquid refrigerant from the liquefying means to the said header; a conduit to conduct the vaporized refrigerant from said header back to the liquefying means; and an automatically operated valve in the header for controlling admission thereto of liquid refrigerant and adapted to maintain the top level of liquid refrigerant in the header above the upper openings of the said pipe loops, whereby a circulation is promoted of the liquid refrigerant through the header and pipe loops.

2. In refrigerating apparatus, the combination of a vaporizer, comprising an expansion chamber; a plurality of pipe loops depending therefrom each with one end opening into the bottom of the expansion chamber and its other end opening into a side thereof at a higher level than the first named end; and means for automatically maintaining liquid refrigerant in the vaporizer up to a level above the ends of the said pipe loops.

3. In refrigerating apparatus, the combination of a tank for anti-freezing liquid formed with a horizontal chamber having one end opening through an upright side of the tank and adapted to receive material to be cooled; a vaporizer associated with the tank and comprising an expansion chamber in the form of a horizontally extending header disposed in the upper part of the tank and a plurality of pipe loops each extending downward and around the said chamber and having its respective ends opening into the said header; and means for maintaining liquid refrigerant in the vaporizer up to a level above the ends of said pipe loops.

4. In refrigerating apparatus, the combination of a vaporizer comprising an expansion chamber and a plurality of pipe loops depending therefrom each with one end opening into said expansion chamber at a higher level than its other end; and means for maintaining a level of liquid refrigerant in said expansion chamber above the uppermost ends of said pipe loops.

5. In refrigerating apparatus, the combination of a vaporizer comprising an expansion chamber and a plurality of pipe loops depending therefrom each with one end opening into said expansion chamber at a higher level than its other end; the said expansion chamber having an inlet opening in the lower portion thereof and an outlet opening therein at a higher level than said inlet opening; means for conducting liquid refrigerant and oil of lower specific gravity than said liquid refrigerant to said inlet opening; and means for conducting vaporous refrigerant and oil away from said outlet opening, the said oil and liquid refrigerant being incompletely mutually soluble; means for maintaining a

level of liquid refrigerant in said expansion chamber above the uppermost ends of the pipe loops and at a substantial distance below the said outlet opening, the said last named means comprising a valve controlling said inlet opening and a float for actuating the valve immersed partly in the liquid refrigerant and partly in the oil in the expansion chamber.

6. In refrigerating apparatus, the combination of a vaporizer, comprising an expansion chamber and a plurality of pipe loops depending therefrom each with both its ends communicating with the interior of the said expansion chamber below the normal liquid level therein; the said pipe loops being disposed unsymmetrically in relation to a vertical plane passing through the horizontal axis of the said expansion chamber; and means for maintaining a body of liquid refrigerant in said expansion chamber and pipe loops.

7. In refrigeration apparatus, the combination of a vaporizer, comprising an expansion chamber and a plurality of pipe loops depending therefrom each with one of its ends opening into the interior of the said header at a higher level than its other end and with the ends below the normal liquid level in said header; the said pipe loops being disposed unsymmetrically in relation to a vertical plane passing through the horizontal axis of the said expansion chamber; and means for maintaining a body of liquid refrigerant in said expansion chamber and pipe loops.

8. In refrigeration apparatus, the combination of a brine tank; an expansion chamber; a plurality of pipe loops depending from said expansion chamber and disposed within said brine tank, each pipe loop having one of its ends opening into said expansion chamber at a higher level than its other end; the said pipe loops being disposed unsymmetrically in relation to a vertical plane passing through the horizontal axis of the said expansion chamber, and being so arranged with respect to each other as to define an elongated space within the interior of the said brine tank; means forming a chamber for receiving food receptacles accessible from one side of the said brine tank and disposed within the space defined by the pipe loops; and means for maintaining a body of liquid refrigerant in said expansion chamber and pipe loops.

9. In refrigeration apparatus, the combination of a cooling chamber having a warm air inlet opening through the upper portion of one side wall thereof and a cool air outlet opening arranged below said first named opening; a cooling unit arranged within said chamber and spaced from the side wall having the warm air inlet opening; said cooling unit including an expansion chamber for

holding liquid refrigerant; means for conducting liquid refrigerant into said expansion chamber; and means for conducting vaporous refrigerant out from said expansion chamber; said last named means comprising an elongated sinuous pipe section connected to said expansion chamber and disposed between the said cooling unit and the side wall of the cooling chamber having the warm air inlet opening.

10. In a vaporizer for refrigeration apparatus, the combination of an expansion chamber; a removable end plate for said expansion chamber having openings there-through for the passage of liquid refrigerant to and vaporous refrigerant from the said expansion chamber; a float valve mechanism carried by said end plate for controlling the amount of liquid refrigerant entering into the said expansion chamber; and depending refrigerant circulating tubes connected to said expansion chamber.

11. In a vaporizer for refrigeration apparatus, the combination of an expansion chamber; a removable end plate for said expansion chamber having an inlet passage for liquid refrigerant and an outlet passage for vaporous refrigerant formed therethrough; means for maintaining a body of liquid refrigerant in said expansion chamber; and a baffle plate carried by said end plate and disposed within the said expansion chamber at a point below said outlet passage for preventing the splashing of liquid refrigerant into the said outlet passage.

12. In a vaporizer for refrigeration apparatus, the combination of a header containing liquid refrigerant; means for maintaining a predetermined liquid level in the header; a plurality of aligned tubes bent to form separate loops and attached at their ends to the said header below the liquid refrigerant level therein; the said loops having their mid portions extending to points relatively remote from said header; and bracing means connecting together the mid portions of the tube loops.

13. In a vaporizer for refrigeration apparatus, the combination of an expansion chamber having inlet and outlet openings therein; means for conducting liquid refrigerant to the inlet openings and for conducting vaporous refrigerant away from the outlet openings; depending refrigerant circulating tubes operatively connected to said expansion chamber; and means within said header for preventing liquid refrigerant from boiling into the said outlet opening.

14. In a vaporizer for refrigeration apparatus, the combination of an expansion chamber having inlet and outlet refrigerant connections; means for conducting liquid refrigerant to said inlet connection and gaseous refrigerant away from said outlet connection; depending refrigerant circulating tubes

operatively connected to said expansion chamber; and a baffle plate located in said expansion chamber below said outlet connection for preventing the liquid refrigerant from boiling into said outlet connection.

15. In a vaporizer for refrigeration apparatus, the combination of an expansion chamber having an inlet opening therein for the admission of liquid refrigerant thereto and an outlet opening for the passage of vaporous refrigerant therefrom; and a baffle plate located within the said expansion chamber and directly over the said inlet opening for preventing the incoming liquid refrigerant from boiling into said outlet opening.

16. In a vaporizer for refrigeration apparatus, the combination of an expansion chamber having an inlet opening therein for the admission of liquid refrigerant thereto, and an outlet opening therein positioned above and spaced from said inlet opening for the passage of vaporous refrigerant from said expansion chamber; and means disposed within said expansion chamber and between the inlet and outlet openings for preventing the incoming liquid refrigerant from boiling into said outlet passage.

17. In refrigeration apparatus, the combination of a compartment to be cooled; a cooling chamber having inlet and outlet openings therein for the passage of air therethrough, and so positioned with respect to said compartment to permit a thermosiphonic circulation of air through said chamber and compartment; a brine tank positioned within said cooling chamber between said inlet and outlet openings with its top surface substantially below the top of the inlet opening; and a refrigerant expansion chamber in the brine tank comprising a header having a substantial part of its body surface extending above the said brine tank in a plane with said air inlet opening and exposed to the warm air entering said chamber.

18. In refrigeration apparatus, the combination of a compartment to be cooled; a cooling chamber having inlet and outlet openings therein for the passage of air therethrough, and so positioned with respect to said compartment to permit a thermosiphonic circulation of air through said chamber and compartment; a brine tank positioned within said cooling chamber between said inlet and outlet openings with its upper surface substantially below the top of the inlet opening; an expansion chamber in the said brine tank and having a substantial part of its body surface extending above the said brine tank in a plane with said air inlet opening and exposed to the warm air entering said chamber; and means for conducting refrigerant to and from said expansion chamber, said means comprising conduits, portions of which being positioned above the said brine tank and between the said expansion

sion chamber and the warm air inlet opening.

19. In refrigeration apparatus, the combination of a refrigerator cabinet; a refrigerator compartment located within said cabinet; a cooling unit within said compartment and so arranged with respect thereto as to cause a circulation of air about said unit and through said compartment; the said cooling unit comprising a brine tank and an expansion chamber comprising a header having a part thereof immersed in the brine and a part extending outside of said brine tank and exposed to the circulating air; and means for conducting refrigerant to and from said header.

20. In refrigeration apparatus, the combination of an expansion chamber; a plurality of tubes bent to form separate loops and attached at their ends to the said expansion chamber; the said tube loops being so arranged with respect to each other as to define within them a continuous space; means for maintaining a level of liquid refrigerant in said expansion chamber above the ends of the said tube loops; a receptacle for food; and means for supporting the said receptacle within the space defined by the said tube loops.

21. In refrigeration apparatus, the combination of an expansion chamber; a plurality of tubes bent to form separate loops and attached at their ends to the said expansion chamber; the said tube loops being arranged in a row extending longitudinally of said header; means for maintaining a body of liquid refrigerant in said expansion chamber; a receptacle for food; and means for supporting the said receptacle within the space defined by said tube loops.

22. In a vaporizer for refrigeration apparatus, the combination of an expansion chamber; a removable plate for closing an opening in a wall of said expansion chamber, said plate having openings therethrough for the passage of liquid refrigerant to and vaporous refrigerant from said expansion chamber; and a float valve mechanism carried by said plate for controlling the amount of liquid refrigerant entering into said expansion chamber.

23. In mechanical refrigerating apparatus, the combination with a compartment to be cooled of a closed system for the circulation of mingled refrigerant and lubricant comprising a refrigerant compressor, a condenser into which the compressor delivers, a vaporizer of the flooded type comprising an expansion chamber and disposed in the said compartment, a conduit to conduct liquid refrigerant and lubricant from the condenser to said expansion chamber; a conduit to conduct the vaporized refrigerant and liquid lubricant from the expansion chamber back to the compressor, and a float

actuated valve in the expansion chamber for automatically controlling admission of the liquid refrigerant and lubricant into said chamber, the last named conduit comprising an elongated sinuous section, disposed within the said compartment, whereby refrigerant held in solution in lubricant passing through said conduit is permitted to vaporize within the bounds of said compartment as it passes back to the compressor.

24. In mechanical refrigerating apparatus, the combination with a compartment to be cooled of a closed system for the circulation of mingled refrigerant and lubricant comprising a refrigerant compressor, a condenser into which the compressor delivers, a vaporizer of the flooded type comprising an expansion chamber and disposed in the said compartment, a conduit to conduct liquid refrigerant and lubricant from the condenser to said expansion chamber, a conduit to conduct the vaporized refrigerant and liquid lubricant from the expansion chamber back to the compressor, a float actuated valve in the expansion chamber for automatically controlling admission of the liquid refrigerant and lubricant into said chamber and means in said expansion chamber for preventing splashing of liquid refrigerant into the last named conduit by the sudden expansion of the refrigerant on entering the vaporizer, said last named conduit comprising an elongated sinuous section, disposed within the said compartment, whereby refrigerant held in solution in lubricant passing through said conduit is permitted to vaporize within the bounds of said compartment as it passes back to the compressor.

25. In refrigerating apparatus, the combination of a vaporizer, a compressor, a condenser, a pipe for conveying liquid refrigerant and lubricant dissolved therein from the condenser to the vaporizer, means adapted in conjunction with said pipe and compressor to maintain a body of liquid refrigerant in the vaporizer and a pipe for conveying lubricant and vaporized refrigerant from the vaporizer to the compressor and comprising a plurality of loops constituting an elongated tortuous passage whereby any liquid refrigerant in the returning lubricant will all be vaporized in passing through said tortuous passage.

26. In a vaporizer for refrigeration apparatus, the combination of an expansion chamber adapted to contain liquid refrigerant and oil and having an inlet opening therein for the admission of liquid refrigerant and oil thereto, and an outlet opening therein positioned above and spaced from said inlet opening for the passage of vaporous refrigerant and liquid oil from the expansion chamber; and means submerged in the liquid in said

- chamber for preventing boiling of refrigerant into said outlet opening.
27. In a vaporizer for refrigeration apparatus, the combination of an expansion chamber adapted to contain substantially a constant quantity of liquid refrigerant and oil, said chamber having an inlet opening for liquid refrigerant and oil and an outlet opening for gasified refrigerant and liquid oil; and a baffle secured within said chamber beneath said outlet opening and below the liquid level therein. 70
- 10 28. In a vaporizer for refrigeration apparatus, the combination of an expansion chamber; a removable end plate for said expansion chamber having openings therethrough for the passage of liquid refrigerant to and vaporous refrigerant from the said expansion chamber, and a float valve mechanism carried by said end plate for controlling the amount of liquid refrigerant entering into the said expansion chamber. 75
- 15 29. In a refrigerating apparatus, a vaporizer comprising a header adapted to contain liquid refrigerant and a plurality of pipe loops secured thereto with both ends of each loop in open communication with said header below the level of liquid contained therein, said pipe loops being disposed in parallel relationship and comprising portions extending laterally beyond said header, and means for maintaining a body of liquid refrigerant in said header and said pipe loops. 80
- 20 30. In a refrigerating apparatus, a vaporizer comprising a header adapted to contain liquid refrigerant and a plurality of refrigerant conduits connected thereto with both ends of each conduit in open communication with said header below the level of liquid therein, one of said ends being disposed at a higher horizontal level than the other end, said conduits being provided with portions extending laterally beyond said header and arranged in parallel relationship, and means for maintaining a body of liquid refrigerant in said chamber and said conduits. 85
- 25 31. In a refrigerating apparatus; a vaporizer comprising a header adapted to contain liquid refrigerant, means for maintaining a predetermined liquid level in the header, a plurality of refrigerant conduits connected thereto with both ends of each conduit in open communication with said header below the level of liquid therein, one of said ends being disposed at a higher horizontal level than the other end, said conduits being provided with portions extending laterally beyond said header and arranged in parallel relationship, and means engaging a plurality of said tubes at a point remote from said header. 90
- 30 32. In a refrigerating apparatus, a vaporizer comprising a header adapted to con-
- tain liquid refrigerant, means for maintaining a predetermined liquid level in the header, a plurality of refrigerant conduits connected thereto with both ends of each conduit in open communication with said header below the level of liquid therein, one of said ends being disposed at a higher horizontal level than the other end, said conduits being provided with portions extending laterally beyond said header and arranged in parallel relationship, and metallic means firmly engaging a plurality of said tubes at a point remote from said header. 95
- 35 33. In refrigerating apparatus, vaporizer means comprising liquid refrigerant containing means, two groups of refrigerant conduits connected to said liquid refrigerant containing means at different horizontal levels, means for connecting the conduits of one group to the conduits of the other group at a point remote from said liquid refrigerant containing means, and means for automatically maintaining liquid refrigerant in said liquid refrigerant containing means at a level above the ends of said groups of conduits. 100
